[57] ABSTRACT

The present invention relates to a new and distinct variety of heath plant named *Erica persoluta* 'Happy', a seedling on unknown pollen and seed parentage, discovered in a field of *Erica persoluta*, which is distinguished from *Erica persoluta* and other varieties known to me by its early flowering habit, dense and compact appearance, natural short growth habit, orchid colored blooms that cover the plume from the base of the stem all the way to the tip of the plant, and its tight, narrow and erect plumes spike-like flower clusters.

1 Drawing Sheet

1

BACKGROUND OF THE INVENTION

This invention relates to a new and distinct plant variety of the Ericaceae family which has been named *Erica persoluta* 'Happy' by the assignee of the invention. This new heather variety was discovered by the inventor as a seedling of unknown pollen and seed parentage growing in a cultivated field of *Erica persoluta*. The new variety was noticed because of its early flowering habit, dense and compact appearance, natural short growth habit, orchid colored blooms which bloom to the tip of the plant, and its tight, narrow and erect spike-like flower clusters.

The new variety is desirable for potted plant culture because of its natural compact, dwarfish growth habit which requires minimal pruning to achieve the abundant branching and full, dense appearance desired.

The distinguishing characteristics of my new variety which differentiate it from *Erica persoluta* and other varieties known to me are:

1. early bloom time of October through mid January,
2. short, dense, compact growth habit,
3. natural abundant branching with minimal pruning,
4. orchid colored blooms which bloom to the tip of the plant, and,
5. tight, narrow and erect spike-like flower clusters.

The distinguishing characteristics of my new variety which differentiate it from *Erica persoluta*, 'Heidi' and 'Rosemarie' are bloom time and color blooms.

	'HAPPY'	'HEIDI'	'ROSEMARIE'	ERICA PERSOLUTA
Bloom	Oct.-	Mid Dec.-	Dec.-Feb.	March
Season	Mid Jan.	Mid Feb.		
Bloom	78C-78D	71C-71D	66D	70A-70B
Color				

Since the inventor's discovery of the new plant, the assignee, under the direction and control of the inventor at Half Moon Bay, has asexually reproduced the new cultivar through successive generations by means of cuttings and has found that its following characteristics remain true from generation to generation and appear to be firmly fixed: early bloom time; shorter, dense, compact growth habit; natural abundant branching which

2

requires minimal pruning; orchid colored blooms which bloom to the tip of the plant; and tight, thin and erect spike-like flower clusters.

5 BRIEF DESCRIPTION OF THE DRAWING

FIG. 1 is a color photograph of a potted plant of the new variety illustrating the overall appearance and form of the plant, including: abundant branching; short height; dense compact appearance; tight, narrow and erect plumes; and blooms all the way to the tip of the plant.

FIG. 2 is a close up view of the plumes of the new variety illustrating the abundance of blooms on the plumes and blooms all the way to the tip of the plant.

10 DETAILED DESCRIPTION OF THE DRAWING

The following is a detailed description of the new variety with color designations according to the R.H.S. Colour Chart published by The Royal Horticultural Society of London, England. The following description is based on observations of well fertilized 4" potted plants of 12 to 16 months of age from initial propagation which were grown outside under saran in a commercial nursery at Half Moon Bay, Calif., where temperature 15 average from 55 to 65 degrees F. during the summer months, and 45 to 55 degrees F. during the winter months.

20 Color designation and other values stated may deviate slightly from the stated values from flowering to 25 flowering, but the deviations will be within the range expected from varying environmental, seasonal, and cultural conditions.

The Plant

30 35 Origin: Seedling.

Parentage:

Seed parent.—Unknown.

Pollen parent.—Unknown.

Classification:

Botanic.—*Erica persoluta* 'Happy'.

Commercial.—'Happy'.

Form: Perennial, compact, woody shrub.

Shape: Upright, stems curving slightly to accommodate fullness of plant.

Height: Mean 12" to 18".

Girth: Mean 8" to 10".

Plant 8,650

3

Branching: Ample, needs minimal pruning.
Growth: naturally compact with woody flexible strength.
Foliage: Abundant, with tiny needle-like leaves over the entire plant.

Size of leaf.—Mean $\frac{1}{8}$ " long.

Shape of leaf.—Acerose like.

Character.—Sulcate.

Color.—R.H.S. 144 A.

Texture.—Smooth.

Hardiness: Can tolerate a temperature range of 28 to 100 degrees F.

Disease resistance: Considerable resistance to fungus type diseases. Common diseases include phythium and phytophthora.

Seed production: Sparse; commercially produced asexually by cuttings.

Effects of weather: Prolonged exposure to hot weather is detrimental to plant appearance. Extended periods of hot, sunny, dry weather will accelerate blooming and cause blooms to decline more quickly, shortening its lasting quality.

In general, the foliage is too tiny to determine further characteristics by plant observation.

The Bud

Size:

Length.— $\frac{1}{8}$ " and less.

Diameter.— $1/10$ " and less.

Rate of opening: progressive and continuous to the tip of the stem.

Petals: Corolline flowers in which the sepals are relatively insignificant.

Color: R.H.S. 78 B to 78 D.

Inflorescence

Blooming habit: Annually, can range from early October through mid January depending upon seasonal weather conditions.

Size of bloom: $\frac{1}{8}$ " by $1/10$ ".

Borne: Spike like clusters with terminal flowers.

Shape: Urceolate.

Appearance: Satiny.

Color: R.H.S. 78 B to 78 C in overall appearance of the plant.

Flower stem:

Length.—Mean $1\frac{1}{2}$ " to 3".

Color.—R.H.S. 177D.

Strength.—Woody and supple.

Discoloration: Does not fade.

Effects of weather: Prolonged exposure to hot weather is detrimental to plant appearance. Extended periods of hot, dry, sunny weather will accelerate blooming and cause blooms to fade and decline more quickly, shortening its lasting quality.

Persistence: Blooms persists long after the stem ceases to draw water. Blooms do not shed easily.

Fragrance: Slight.

Lasting quality:

On plant.—6 to 8 weeks.

As a cut flower.—2 weeks.

The outstanding characteristics of this new plant resides in its early blooming from October through mid January, whereas *Erica persoluta* does not begin to bloom until March. Its natural short, compact growth habit makes it suitable for pot plant culture, whereas

4

Erica persoluta is of the cut flower variety and is taller.

5	PLANT	'HEIDI'	'ROSE-MARIE'	'ERICA PERSOLUTA'	NEW CULTIVAR
	Height	a 4" pot will be 8" or 9" high in 18 mons. growing time with little or no pruning	Same	a 4" pot will be 10" to 12" high in 18 mons. growing time with numerous pruning	a 4" pot will be 13" to 15" high in 16 mons. growing time with minimal pruning
10	Form	short, dense appearing, compact woody shrub	Same	Same	Same
15	Shape	Upright, stems curving slightly to accommodate fullness of plant	Same	Upright, stems spreading to produce fullness of plant	Upright, stems curving slightly to accommodate fullness of plant
20	Branching	naturally generous, minimal or no pruning needed	Same	generous, several prunings necessary (4-5) to encourage branching	ample, minimal (1-2) prunings necessary to encourage branching
25	Growth	upright but naturally short and branching with woody, flexible strength	Same	Same	Same
30	Blooming Season	annual, mid Jan. to mid Feb.	annual, Dec.-Feb.	annual, early March through late March	annual, early Oct. through mid Jan.
35	Foliage Color	R.H.S. 143A	R.H.S. 144A	R.H.S. 143A with 59A streaking through the leaves	R.H.S. 144A
40	Size Shape	$\frac{1}{8}$ " spike-like, with stiff, erect stems; Acerose	Same	Same	Same
45	Quantity Bloom	Abundant	Same	Same	Same
50	Size Borne	$\frac{1}{8}$ " $\times$ $1/16$ " in clusters with terminal buds	Same	$3/16$ " $\times$ $1/16$ " Same	$\frac{1}{8}$ " $\times$ $1/10$ " Same
55	Shape Color	Urceolate R.H.S. 71C-71D	Same R.H.S. 66D	Ovoid R.H.S. 70A-70B	Urceolate R.H.S. 78B-78C
	Rate of opening:	rapid, progressive and continuous beginning at the base of the stem and progressing to the tip of the stem	Same	Same	Same
60					

I claim:

1. A new and distinct hybrid plant variety of the Heath family substantially as herein shown and described.
